We claim the ornamental design for a dispenser fitment, as shown and described.

DESCRIPTION

FIG. 1 is a perspective view of the dispenser fitment; FIG. 2 is a front view of the dispenser fitment; FIG. 3 is a back view of the dispenser fitment; FIG. 4 is a right side view of the dispenser fitment; FIG. 5 is a left side view of the dispenser fitment; FIG. 6 is the top view of the dispenser fitment; and, FIG. 7 is the bottom view of the dispenser fitment. In the drawings, the broken line showing of a dispenser fitment depicts environment and forms no part of the claim. The dispenser fitment is shown with a symbolic break in its length. The dash-dot-dash lines represent boundaries of the claimed design and form no part thereof.
